UNITED STATES PATENT OFFICE.

WILLIAM H. WADDELL, OF LEXINGTON, VIRGINIA.

ELECTRICAL RAILWAY-SIGNALING.

SPECIFICATION forming part of Letters Patent No. 400,525, dated April 2, 1889.

Application filed August 21, 1888. Serial No. 283,357. (No model.)

To all whom it may concern:

Be it known that I, WILLIAM H. WADDELL, of Lexington, in the county of Rockbridge and State of Virginia, have invented certain new and useful Improvements in Electrical Railway-Signals; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in electric signals to prevent accidents on rail-ways.

The object of my invention is to provide an improved electrical railway-signal, whereby, when two railway-trains approach within cer-tain distances of each other, one or more sig-nals will be sounded upon one or both of the trains, thereby notifying the engineers and giving them time in which to stop their trains before a collision occurs.

With these ends in view my invention con-sists in certain novel features of construction and combinations of parts, more fully de-scribed hereinafter, and particularly pointed out in the claims.

Referring to the accompanying drawings, Figure 1 is a top plan of a portion of a rail-road-track and two approaching cars provided with my improved device. Fig. 2 is a side elevation of the same. Figs. 3 and 4 are de-tail views of different forms of movable con-tact-arms carried by and moving with a car and bearing upon the parallel conductors, and Fig. 5 is a detail view of one pair of contacts. Fig. 6 is a diagrammatic representation of two cars following each other with conductors, &c., and showing one car provided with a switch, whereby the battery can be connected with the bell and contacts on one side of the car or with the contacts on the opposite side.

In the drawings, the reference-letter A in-dicates a railroad-track provided with two pairs of parallel conductors, B B', located on opposite sides of the track, with the single conductors of each pair insulated from each other and located a suitable distance apart. Said conductors may be placed between the rails or outside of the same, upon the ties, or

they can be secured to suitable insulators at any desirable height. Each pair of conductors is formed in sections of a suitable length— say, two miles—and between the sections there are breaks, as at E, so that the different sec-tions are insulated from each other, and, further, the sections on opposite sides of the track overlap each other, as shown in Fig. 1— that is, the breaks between the sections of the conductors on one side of the track occur ap-proximately opposite the centers of the sec-tions on the opposite side of the track. Each section of the conductors is preferably pro-vided with one or more circuit-breakers, F, located within its length, and consisting of two inclines extending in opposite directions and in the vertical plane of the conductors. Said inclines extend above and cover the con-ductors and meet at their upper ends to form a continuous surface.

D D', Fig. 1, indicate two cars or trains moving toward each other and each provided with a transverse beam or shaft, G, or other suitable material, to which are loosely pivoted or hinged the upper ends or contact carriers or arms, H H H' H', to allow the free ends of the same a vertical movement. In the pres-ent instance there are four contact-carriers— two on each side, one for each conductor—and at their lower free ends said carriers H are provided with suitable contacts, g g g' g', such as rollers, as seen in Fig. 3, coiled unin-sulated wire, as seen in Fig. 4, or any other suitable sliding contacts which slide upon their respective conductors, as clearly shown. The two contacts on the right side (prefera-bly) of each car or engine are insulated from each other and connected with the opposite poles of a battery, i, by wires 1 2, and the two contacts on the other side of the car or engine are also insulated from each other and con-nected with an electric bell or other suitable alarm, j, by wires 3 4. Thus it will be readily seen that when two trains are moving toward each other there will be no closed circuit un-til one pair of contacts of each train reaches the same section, when the circuit will pass from one pole of the battery on one train through, say, wire 2, connected with that pole to a mov-able contact, g, connected with wire 2 through a conductor, B', upon which contact g slides to a contact, g, sliding on that conductor and

- on the opposite train through wire 4 to and ringing the bell and back again through wire 3, a movable contact, g' , sliding on the other parallel conductor, B' , conductor B' , a contact, 5 g , sliding on the same on opposite train, and from contact g to opposite pole of battery by wire 1, thereby notifying the engineer on one of the trains, and as the trains approach nearer to each other a circuit will be closed on the 10 opposite side of the track, and the bell in the other engine will be rung, the course taken by this circuit being similar to that just described, the positions of the battery and bell being reversed, (*i. e.*, on opposite trains and 15 opposite sides from those included in the first circuit,) and the conductors B on the opposite side of the track from the connection between the trains. When the contacts pass over the inclines or circuit-breakers F , of 20 course the circuit will be broken, the bell ringing again as the contact touches the conductors on the other side of the incline, thus making the alarm more noticeable by having it sound at intervals.
- 25 By means of an ordinary switch-board the battery on an engine can be changed from right to left. (See Fig. 6.) This is necessary when the trains are following each other in the same direction; or, instead of the switch-board, a battery can be interposed between the contacts connected with the bell and in 30 circuit with the bell. (See Fig. 3.)
- If necessary, the hinged arms or contact-holders can be provided with a spring, J , 35 (see Fig. 5,) to hold the contacts yieldingly in engagement with the parallel conductors to allow for inequalities of the conductors and rapid motion of the train.
- If the conductors on the opposite side of 40 the track were not formed in overlapping sections, but the breaks in the sections were opposite each other, two trains might meet at the breaks without even notifying each other. The pivoted contacts preferably slide after 45 the car, as shown in Fig. 2.
- The great advantages and utility of the herein-described invention can be readily seen and understood by all railway men and others; hence it is not considered necessary 50 to fully enumerate the same herein.
- It is clearly evident that various changes might be resorted to in the form and arrangement of the parts described without departing from the spirit and scope of my invention; 55 hence I do not wish to limit myself strictly to the construction herein set forth.
- What I claim is—
1. In an electrical railway-signal, the combination, with a track, of two parallel pairs 60 of conductors normally out of circuit insulated from the ground and located on opposite sides of the track, each pair of conductors

having no electrical communication with the other pair, and the conductors of each pair being parallel and insulated from each other 65 and divided into non-communicating sections, the breaks between the sections of the pair of conductors on one side of the track being located approximately opposite the centers of the sections of the pair on the opposite side, 70 for the purpose set forth.

2. An electrical railway-signal comprising two pairs of parallel conductors insulated from each other and from the ground and located on opposite sides of a railroad-track, 75 said conductors being normally out of circuit and the conductors of each pair insulated from each other and divided into non-communicating sections, two pairs of contacts carried by and on opposite sides of a car or 80 engine, said contacts being insulated from each other and each electrically engaging and sliding on a separate conductor, the two contacts on one side being connected, respectively, with the opposite poles of a battery 85 carried by the engine, and the two contacts on the opposite side being included in a circuit containing a bell or alarm, all operating in the manner and for the purpose substantially as set forth. 90

3. An electrical caution-signal for railways, comprising two pairs of parallel conductors located on opposite sides of a track and insulated from each other, two pairs of contacts carried on opposite sides of a car or engine 95 and electrically engaging said conductors, and inclined circuit-breakers located a suitable distance apart along and rising above said conductors to momentarily throw the contacts from engagement with the conductors as they pass over them for the purpose of intermittently sounding the alarm, substantially as set forth. 100

4. In an electrical caution-signal for railways, two pairs of hinged or pivoted arms located in opposite sides of a car or engine and each carrying a contact insulated from the others, and each adapted to electrically engage a separate conductor extending along the track, the two contacts on one side being 110 electrically connected with the opposite poles and forming the terminals of a battery carried by the car or engine, and the two contacts on the opposite side forming the terminals of a circuit including a bell or alarm, 115 all operating substantially as set forth.

In testimony that I claim the foregoing as my own I affix my signature in presence of two witnesses.

WILLIAM II. WADDELL.
